UNITED STATES PATENT OFFICE.

BENJAMIN F. STUART, OF SAN ANTONIO, TEXAS.

DESIGN FOR A BANK-CHECK.

58,639.

Specification for Design.

Patented Aug. 2, 1921.

Application filed November 24, 1919. Serial No. 340,413. Term of patent 3½ years.

To all whom it may concern:

Be it known that I, BENJAMIN F. STUART, a citizen of the United States, residing at San Antonio, in the county of Bexar and State of Texas, have invented a new, original, and ornamental Design for Bank-Checks, of which the following is a specification, reference being had to the accompanying drawing, forming part thereof.

The figure is a face view of a bank check, showing my new design.

I claim:

The ornamental design for a bank check, as shown.

BENJAMIN F. STUART.
